UNITED STATES PATENT OFFICE

EVERETT C. LEWIS, OF PROVIDENCE, RHODE ISLAND, ASSIGNOR TO UNIVERSAL WINDING COMPANY, OF BOSTON, MASSACHUSETTS, A CORPORATION OF MASSACHUSETTS

COP OR CONE HOLDER

Application filed December 13, 1926. Serial No. 154 462.

This invention relates to cone-holders or mandrels for use with winding machines and other textile apparatus and consists of improvements in the construction and 5 method of operation of the same.

The invention consists in general in providing a rotatable holder or mandrel for supporting a conical paper tube or core on which yarn, thread or other attenuated material is to be wound.

A particular object of the invention is to provide a device of the type specified which will automatically center and align conical tubes of varying taper, while gripping the 15 tube on the holder to secure it rotatively therewith and to hold it from longitudinal displacement thereon.

Another object of the invention is to provide a cone-holder of the type specified having frictionless bearings which require no lubrication.

Another object of the invention is to provide a cone-holder of simplified structure which is economical to manufacture and of 25 greater durability and efficiency in use.

Further objects of the improvement are set forth in the following specification which describes a preferred embodiment of the invention as illustrated by the accompanying 30 drawings. In the drawings:

Fig. 1 is a longitudinal sectional view of the improved cone-holder, taken in a plane intersecting its axis of rotation;

Fig. 2 is a side view of the cone-holder 35 slightly reduced in scale and illustrating a cone-tube of certain taper fitted thereto;

Fig. 3 is a similar view showing the self-centering means as adjusted to the interior of a cone-tube of different taper; and

Fig. 4 is a view showing the manner in which the cone-holder is operated to grip or release the cone-tube or shell placed thereon.

Referring to the drawings, 2 designates a 45 "dead" spindle which is hinged to swing outwardly from an arm 3 forming a part of or connected with the winding machine or other apparatus.

As herein shown the spindle 2 has an enlarged flat-sided butt 4 which is fitted to a

slot at the end of the arm 3 and pivoted to turn on a cross-bolt or stud 5 extending through the sides of the arm. The butt-end 4 of the spindle 2 is formed with a V-shaped notch 6 adapted to receive the bent end 7 of a flat spring 8 which is fastened to the side of the arm 3 by a bolt 9. The spring 8 normally holds the spindle 2 in position projecting at right-angles to the arm 3, the end of the spring being releasable from the 60 notch 6 under pressure to permit the spindle and its cone-holder to be swung outwardly into the position illustrated in Fig. 4 of the drawings. This arrangement, which is common to devices of the present type, provides for swinging the cone-holder out of operative position when placing the cone-tube thereon and when doffing the completed cone or cop therefrom. The swinging action of the spindle is also employed to operate the holding-means for the cone-tube, either to secure the tube in place on the holder or to release it therefrom. The construction of the cone-holding or securing-means forms one feature of the present invention and will be more specifically described hereinafter.

The spindle 2 is turned down or reduced in diameter at 11 to receive a collar or bearing-ring 12 which is forced tightly thereon against the shoulder 13. The bearing-ring 12 is provided with a race for a series of balls 15 rotatably supporting an outer ring or annulus 16. The ring or annulus 16 forms an end thrust-bearing for the rotatable shell or mandrel 20 which constitutes the holder for the cone-tube C.

The cone-holder shell 20 is constructed with a relatively long sleeve-like hub 21 which is bored to receive a tubular sleeve or bushing 22, preferably constructed of impregnated wood, fiber or other oil-less bearing material. The bushing 22 is forced into the bore of the hub 21 to secure it rotatively therewith; its bore being fitted to the reduced portion of the spindle 2 to permit it to rotate freely thereon. The outer end of the spindle 2 is bored axially to receive an expanding bolt 25. The inner end of the bore is threaded to receive the threads of 100

the bolt while its outer end is of tapered or conical form and split longitudinally at 26. The outer end of the bolt 25 has a similar conical section fitted to the tapered outer end of the bore in the spindle with the sides of its projecting portion flattened off at 27 to provide a head for turning the bolt with a wrench. Surrounding the outer end of the spindle 2 is a collar 28 which is secured thereon by expanding the split end of the spindle through means of the taper-ended bolt 25. The collar 28 abuts the outer end of the bushing 22 to hold the shell 20 longitudinally of the spindle 2, the opposite end of the hub 21 of the shell being held by the thrust-bearing 16.

The outer end of the hub 21 of the shell 20 is reduced in diameter at 29 to adapt it to receive a sliding sleeve or collar 30 which constitutes the self-adjusting means for centering the cone-tube C on the holder. The collar 30 is provided with a slot 31 which is engaged by a screw 32 screwed into the reduced portion 29 of the hub 21. A helical spring 33 surrounds the reduced portion 29 of the hub 21 between the collar 30 and a shoulder 34 on the hub. The spring 33 tends to urge the collar 30 outwardly on the hub 21 to hold it snugly within the tapered interior of the cone-tube or shell C. When tubes of different taper are applied to the holder the collar 30 adjusts itself longitudinally thereof to center and aline the forward end of the tube in the manner as later explained.

The rearward or butt-end of the tube or shell C is received on an enlarged conical boss or annulus 35 disposed at the base end of the shell or holder 20 and supported from a radial web 36. The shell-like boss or annulus 35 overhangs the rearward end of the hub 21 of the holder and its periphery is of a taper to adapt it to substantially fit the interior of the larger base end of the cone-tube C. In some cases, however, the taper or angle of inclination of the cone-tube C may vary slightly, for instance, with tubes adapted for different makes of winding machines. In such cases the larger or base end of the tube will still fit quite snugly about the enlarged boss or annulus 35 of the holder 20 when forced thereon, and the slideable collar 30 at the forward end of the holder will adjust itself longitudinally of the tube to firmly engage the interior thereof, whereby to center the tube on the holder, or, in other words, to hold it concentrically with respect thereto.

The means for securing the cone-tube C in place on the holder is carried by the enlarged section or annulus 35 and comprises a plurality of rockable dogs or gripper levers 40. As herein shown there are two dogs 40, constructed in the form of flat blades having teeth 41 adapted to bite into

the interior of the cone-tube C. The blades 40 are held in radial slots 37 cut through the shell 35 and its flange or web 36, the bottom of the slots 37 intersecting the periphery of the hub 21. The blades 40 have rounded ends which rest in the bottom of the slots 37 to adapt them to pivot thereon whereby their opposite ends may be moved radially outward to engage the teeth 41 with the interior of the cone-tube C or to withdraw them inwardly therefrom. The blades 40 are held in place in their slots 37 by means of a split spring-ring or annulus 42 sprung into a circumferential groove 43 scored in the periphery of the shell 35. The ring 42 passes through notches 44 in the blades 40 and is prevented from turning circumferentially of the groove 43 to release the blades by means of a pin 45 driven into the shell 35 intermediate the ends of the ring, see Fig. 2.

The free ends of the blades 40 are formed with circular ears or lobes 39, the edges of which are engaged by the tapered periphery of a sliding sleeve 46. The sleeve 46 is adapted to slide on the reduced inner end 47 of the hub 21 of the shell or holder 20 and is formed with an inclined surface 48 for wedging the blades 40 radially outward. The forward end of the sleeve 46 is reduced in diameter to form a shoulder 49, and a helical spring 50 compressed between the shoulder and the web 36 of the holder 20 acts to slide the sleeve to the right as viewed in Fig. 1. The force of the spring 50 therefore tends to slide the sleeve 46 to cause its tapered portion 48 to wedge the blades 40 outwardly to press their prongs or teeth 41 into engagement with the interior of the cone-tube C. Preferably, the sleeve 46 is provided with a circumferential fin or flange 52 which is adapted to bring up against the sides of the ears 39 on the blades 40 to prevent the sleeve from being slid too far to the right as viewed in Fig. 2. This construction eliminates the possibility of the sleeve being forced into frictional contact with the side of the arm 3.

To release the blades 40 from holding engagement with the cone-tube C the sleeve 46 is slid to the left against the pressure of the spring 50, this action being accomplished by swinging the cone-holder bodily into the position shown in Fig. 4. When the cone-holder is swung around in this manner with the spindle 2 pivoting on the bolt 5 the rounded cam surface 51 at the end of the arm 3 will engage against the end of the sleeve 46 to slide the latter to release its wedging action on the dogs or blades 40. When the blades 40 are thus released from the wedging action of the sleeve 46 the constrictive spring-action of the ring 42 will draw them inwardly to disengage their teeth 41 from the interior of

the cone-tube C as clearly shown in Fig. 4 of the drawings.

The method of operation of the complete device is as follows: When the device is used in connection with a winding machine the cone-holder 20 is first swung outwardly into the position shown in Fig. 4 to render it convenient to place the cone-tube C thereon. The operator simply grasps the cone-tube C in the hand and forces its larger end snugly onto the exterior of the boss or shell 35. Where the tube C is of relatively steep pitch or taper the engagement of the sliding collar 30 with the interior of its smaller end will force the collar rearwardly against the pressure of the spring 33. In other cases where the cone-tube is of less pitch or taper the collar 30 will be held farther out toward the end of the cone-holder to maintain its outer edge bearing against the interior of the cone-tube to center the latter with respect to the holder, see Fig. 3.

After the cone-tube C has been slid onto the holder 20 in this manner the operator swings the holder bodily inward to set it in cooperative relation with respect to the other elements of the winding machine. As the operator moves the holder in this manner, meanwhile pressing the cone-tube C towards the base end of the holder, the sleeve 46 is released from the camming action of the arm 3, and thereupon the spring 50 comes into play to slide the sleeve 46 longitudinally to cause it to wedge the dogs 40 outwardly to pierce their teeth 41 into the interior of the tube C which is made of fiber or similar yieldable material. The tube C is thus gripped securely to the holder with its interior supported at widely spaced points to hold it concentrically with respect to the axis of rotation of the holder.

It will be observed from the above that my invention provides a particularly simple, compact and efficient device for the purpose specified and one in which the parts are designed for economical manufacture. The operating-mechanism of the device is practically automatic in action and is adapted to not only grip the tube to the holder, but to center it thereon while providing for the use of tubes of different taper or pitch. This latter feature is of considerable importance, since heretofore where the cone-tubes varied slightly in size or in taper they could not be held securely on the holder or mandrel. That is to say, some tubes would fit properly while others could not be held securely and would become loose under the winding or other operation.

As another feature of the invention the present improved device does away with the necessity for oiling the mandrel or holder while providing for greater durability of its bearings. The elimination of lubrication prevents oil from being thrown or spat-

tered on to the material being wound or otherwise transferred or treated and therefore saves damage to and waste of the yarn and thread.

While the device is herein illustrated in a preferred embodiment it is to be understood that various modifications may be made in the structure and arrangement of its parts without departing from the spirit or scope of the invention.

Therefore, without limiting myself in this respect, I claim:

1. In a device of the type specified, the combination with a dead spindle, of a ball-bearing at one end thereof, a conical shell having a hub cooperating with the ball-bearing to take the end thrust of the shell, a bushing of friction-reducing material held in the bore of the hub and rotatable on the spindle, and means for retaining the shell in place on the spindle.

2. In a device of the type specified, the combination with a dead spindle, of a ball-bearing at one end thereof, a conical cone-tube holder having a hub arranged with its end engaging the ball-bearing to take the end thrust thereof, a bushing of friction-reducing material inserted in the hub of the holder and rotatable on the spindle, and a collar secured to the outer end of the spindle abutting the end of the bushing to take the forward and thrust of the holder.

3. In a device of the type specified, the combination with a dead spindle, of a cone-tube holder having an extended hub, a bushing of friction-reducing material fitted to the bore of the hub and rotatable on the spindle, a ball-bearing on the spindle for taking the end thrust of the holder in one direction, a collar at the opposite end of the spindle for taking the end thrust of the holder in the other direction, and means for expanding the end of the spindle to secure the collar in place thereon.

4. In a device of the type specified, the combination of a dead spindle having an axial bore at one end which is interiorly threaded at its inner end and tapered at its outer end, said spindle being split to adapt its end to expand, a screw having a tapered end-portion fitted to the bore in the end of the spindle, a cone-holder rotatable on said spindle, and a collar surrounding the end of the spindle and held in place by the expanded split portion thereof to retain the cone-holder in position on the spindle.

5. In a device of the type specified, a cone-tube holder formed with radial slots, blades loosely mounted in said slots with their ends engaging the bottom thereof, means for holding the blades longitudinally of the slots, and means acting on the blades to rock their ends radially outward to engage the interior of the cone-tube.

6. In a cone-tube holder having a shell

fitted to receive the base end of the tube and provided with radial slots, the combination of blades received in said slots with their forward ends engaging the bottom thereof and their rearward ends provided with means for engaging the interior of the cone-tube, a spring-ring engaging the blades to hold them in place in the slots and tending to rock the blades inwardly to release their ends from the tube, and means for wedging the blades radially outward in the slots to engage their ends with the tube to secure the latter in place on the holder.

7. A cone-tube holder having a conical shell for receiving the base end of the cone-tube, said shell provided with radial slots and a circumferential groove intersecting the slots, blades held in said slots with their ends engaging the bottom thereof and provided with notches registering with the circumferential groove on the shell, a spring-ring seated in the groove on the shell and engaging the notches in the blades, and means acting upon the ends of the blades to rock the latter radially outward against the constrictive action of the spring-ring whereby to engage the blades with the cone-tube to secure it in place on the holder.

8. In a cone-tube holder, the combination of a conical shell for receiving the base end of the tube, said shell formed with radial slots and a circumferential groove intersecting said slots, blades received in said slots with their ends engaging the bottom thereof and provided with notches registering with the circumferential groove on the holder, a spring-ring seated in the groove on the holder and engaging the notches in the blades to hold them in place in the slots while adapting them to rock therein, a sleeve slidable axially of the holder and formed with a tapered periphery adapted to act with a wedging effect on the blades to force them radially outward to engage them with the cone-tube held on the holder, and means for sliding said sleeve.

9. In a cone-tube holder, the combination of a shell for receiving the tube, radial blades rockably mounted on the shell and formed with ears at their ends, and a sleeve slidable axially of the shell and having a tapered periphery for engaging the ears on the blades to move the latter radially outward to engage them with the tube on the holder, said sleeve provided with a circumferential flange adapted to contact with the sides of the ears on the blades to limit the sliding movement of the sleeve.

In testimony whereof I hereunto affix my signature.

EVERETT C. LEWIS
